UNITED STATES PATENT OFFICE.

SAMUEL CUNNINGHAM, OF NEWTON HIGHLANDS, MASSACHUSETTS, ASSIGNOR TO THE WILLIAM CARTER COMPANY, OF NEEDHAM HEIGHTS, MASSACHUSETTS, A CORPORATION OF MASSACHUSETTS.

INFANT'S BAND.

1,413,459.

Specification of Letters Patent. Patented Apr. 18, 1922.

Application filed July 31, 1920. Serial No. 400,469.

To all whom it may concern:

Be it known that I, SAMUEL CUNNINGHAM, a citizen of the United States, and a resident of Newton Highlands, in the county 5 of Middlesex and State of Massachusetts, have invented an Improvement in Infants' Bands, of which the following description, in connection with the accompanying drawings, is a specification, like characters on the 10 drawings representing like parts.

This invention relates to under garments, and particularly to knitted infants' bands, though within the scope and purpose of the invention, it may be put to other uses.

15 In order that the principle of the invention may be clearly set forth, I have disclosed several embodiments thereof in the accompanying drawings, wherein—

Fig. 1 is a front elevation of a knitted infant's band or undershirt disclosing the preferred embodiment of the invention;

Fig. 2 is a vertical cross section along a vertical median line of Fig. 1;

25 Figs. 3 and 4 are views similar to Figs. 1 and 2 respectively of another form of the invention;

Fig. 5 is a front elevation of the lower part of an infant's band of a still further modified construction; and

30 Fig. 6 is a vertical central section of the construction shown in Fig. 5.

Referring more particularly to the drawings and first to that form of my invention shown in Figs. 1 and 2, 1 indicates the body 35 portion of an undergarment and which preferably is a knitted infant's band having integral therewith shoulder straps 2, 2. Desirably the garment having said parts is integrally knitted as a circular or seamless

40 tube, but my invention is not limited in this respect. Desirably the garment is provided with a suitable reenforcing edge formation 3 preferably constructed by overseaming or other like sewing operation, so as to form an

45 elastic seam. Desirably the wales of the knitted fabric extend lengthwise of the body portion of the garment and preferably the garment is formed by rib knitting. While the garment may be employed for other uses, it is primarily intended as an infant's band, and to that end has at its lower end a formation or formations adapting it for the attachment thereto of some suitable article, such as an infant's napkin or diaper. While

to this end, any suitable construction may be 55 provided, I preferably provide the lower end of the garment, and preferably though not necessarily at the front thereof, with a reentrant portion indicated at 4, 4 and of any suitable extent. 60

Desirably integral with the body of the garment and extending from the upper end of said reentrant portion, I provide a strip 5, which, as clearly indicated in Figs. 1 and 2, is substantially twice the length of 65 the reentrant portion, so that it may be folded upon itself at the point 6 to provide a loop having an upturned end 7 adapted to be secured, and desirably detachably, to the main portion of the garment or to the 70 upper part of the strip 5. In the disclosed form of my invention, I have represented the upper part of the strip 5 as having a button 8, the upturned portion 7 of the strip 5 having a buttonhole 9. The strip 5 may 75 be formed in any suitable way, and preferably by continuing the knitting upon a number of needles corresponding to the width of the strip 5 after the body 1 of the garment has been completed. Thereafter 80 the garment may be slit at the front to provide the reentrant portion 4 and the garment is then suitably finished at the edge, as indicated at 3, or if desired the knitting may be interrupted upon one or more needles 85 at each side of the strip 5, so as to provide the reentrant portion.

The strip 5 folded into a loop as described is adapted to receive and preferably is provided with some suitable means for the attachment of a napkin or diaper, such, for example, as a safety pin 10, which may be furnished with the garment as a constituent part thereof. At the rear of the garment the napkin or diaper may be attached in any 90 suitable manner, and I may or may not provide some special formation to this end. 95

In Figs. 3 and 4, I have indicated a second form of my invention. Therein I have indicated the body of the garment at 11, 100 which body portion may be formed as already described or in any other suitable manner, as, for example, from one or more pieces suitably seamed together. The shoulder straps 12, 12 are preferably integral 105 with the body portion, and some suitable binding or edge formation 12' may be provided. In this form of my invention, the

body part 11 is provided at the front with an integral strip continuation 13 adapted to be folded upon itself as shown in Fig. 4, to provide a loop for the reception of a 5 safety pin 14 or like device. The strip 13 at its end 15 is adapted to be secured in any suitable manner to the body portion 1, as, for example, by pinning, buttoning or stitching 15'. At the rear the garment is preferably provided with an integral strip continuation 16.

The napkin or diaper may be secured to the strips 13, 16. In addition to the foregoing means or as a substitute therefor, the 15 garment may be provided with a tape or tapes 17 sewed throughout substantially the length thereof to the body portion of the garment and passing over the shoulders as indicated at 18. In this manner, loop portions 20 19, are provided which are adapted to receive safety pins or like devices 20 as indicated in Fig. 4.

In Figs. 5 and 6, I have shown still another form of my invention. Therein the 25 lower part of the body of the garment is indicated at 30. One part of the garment, and desirably the front, is provided with an integral strip formation 31, and I have herein represented said strip formation and the 30 lower part of the body as having a suitable binding or reenforced edge 32. To one face of said strip portion 31 and desirably to the front thereof, I attach a preferably knitted strip 33 which is folded upon itself at 34 to 35 provide a return portion 35, herein shown as having a buttonhole 36 to receive a button 37 secured by thread 38 to the several underlying parts. If desired, the rear of the garment may be provided with any of 40 the forms shown in the foregoing figures, but desirably I provide an integral formation 39 to which the diaper or napkin may be attached.

In each of the several forms of my invention, the body of the garment may be of the 45 character disclosed or referred to in connection with the description of Figs. 1 and 2.

Having thus described certain embodiments of my invention, I desire it to be understood that although specific terms are 50 employed, they are used in a generic and descriptive sense and not for purposes of limitation, the scope of the invention being set forth in the following claims.

55 Claims—

1. An undergarment formed of knitted

material and having at its lower end a reentrant portion, from the base of which extends a flap of substantially the width of 60 said reentrant portion and integral with the body of the band, said flap being adapted to be folded into a loop for the reception of a safety pin or other fastening device.

2. An infant's undergarment having at 65 its lower end a reentrant portion from the base of which a flap extends integral with the body of the garment, said flap being adapted to be folded upon itself into a loop to receive a safety pin or like fastening device, a button upon the reentrant portion, 70 and a buttonhole in the end of the flap.

3. A knitted undergarment having permanently at its lower end a knitted extension adapted to be folded upon itself into a 75 loop for the reception of a safety pin or other fastening device, said extension having buttoning means whereby to secure it in its folded condition to the body of the garment.

4. An undergarment formed of knitted 80 material and having at its lower edge at substantially midway between the sides of the garment a relatively narrow reentrant portion, a flap of substantially the full width of 85 said reentrant portion integral with the body of the garment and of substantial length so as to be folded upon itself for the reception of a safety pin or other fastening device; and means to secure said folded flap in holding position.

5. An undergarment formed of knitted 90 material and having at its lower edge at the middle of the front a relatively narrow reentrant portion, from the base of which a flap integral with the body of the garment 95 extends, said flap being of substantially twice the length of the reentrant portion and of substantially the full width thereof and adapted to be folded for the reception of a safety pin or other fastening device, and a 100 button and buttonhole construction for securing said flap in folded position.

6. An undergarment formed of knitted 105 material having at its lower end a relatively narrow reentrant portion, from the base of which a flap 5, 7 extends, said flap being of substantially the full width of the reentrant portion, and button and buttonhole means 8, 9 for securing the flap in folded position.

In testimony whereof, I have signed my 110 name to this specification.

SAMUEL CUNNINGHAM.
